CONVEYER MECHANISM

William J. Taylor, Syracuse, N. Y., assignor to
The Lamson Company, Syracuse, N. Y., a corporation of Massachusetts

Application July 30, 1935, Serial No. 33,847

8 Claims. (Cl. 198—127)

This invention relates to an improvement in conveyor mechanism more particularly in such mechanism of the live roller type comprising a plurality of article transporting rollers rotated by a driving cable.

Objects of this invention are briefly to provide in a live roller conveyor mechanism, means for deflecting articles from the main line to a branch line and automatic means for facilitating the separation of the articles into groups.

These and other objects of the invention will be fully understood from an examination of the following detailed description thereof and of the drawings which form a part of said description and in which—

Fig. 1 is an enlarged plan view of a live roller section provided with an article deflector mechanism embodying this invention;

Figs. 2 and 3 are side elevation and cross-sectional views respectively thereof;

Figs. 4 and 5 are enlarged views partly in cross section of details of the deflector mechanism;

Fig. 6 is a diagrammatic view illustrating the operating circuit for the deflector mechanism;

Figs. 7, 8, and 9 are side elevation, cross-sectional and plan views respectively of an article actuated control for separator mechanism;

Figs. 10 and 11 illustrate the article contacting arm of such control;

Fig. 12 is an enlarged sectional view of a detail of the arm shown in Figs. 10 and 11.

Fig. 13 is a view in elevation of the ratchet wheel of the control;

Fig. 14 is a view of electrical element of the control; and

Fig. 15 is a diagrammatic view illustrating an electrical layout by which the control is caused to operate a deflector mechanism.

This invention relates to a conveyor system which includes one or more live roller sections. The term "live roller section" is used to designate a conveying instrumentality comprising a plurality of rollers over which the articles travel and a

cable or the like which is held in contact with the rollers and driven by a motor or other means to rotate the rollers and cause the latter to advance the articles. In Fig. 1 which illustrates a portion of a conveyor system is shown a live roller section comprising a plurality of rollers 107 rotated by a suitably advanced cable 52.

The live roller section indicated on Fig. 1 includes a branch station or storage line 101 leaving from the main line and to which articles are deflected as desired either continually or intermit-

tently. The branch line 101 may be of any desired type and is here shown as a gravity roller conveyor having a plurality of free rollers over which the articles travel. Suitably supported across the main line as upon uprights 102 are a pair of angle bars 103, one at each end of the junction of the main line with the branch line. Mounted at their ends upon the bars 103 are a channel bar 104, an angle bar 105, and a rod 106, the bars 104 and 105 and the rod 106 being all parallel to each other as shown particularly in Fig. 1. Between the cross bars 103 are mounted the live rollers 107, hereinbelow referred to as deflector rollers. Each roller 107 is carried by a U-shaped bracket 108 in the end walls of which the roller is rotatably mounted. Each bracket 108 is pivoted upon the bar 104 by a pin 109 and is supported at one end by an antifriction bearing 110 which surrounds the pin 109 and at the other end by the rod 106 upon which it rests freely. Associated with each roller 107 is a sheave 111 mounted upon the bar 106 by a bracket 112. Each sheave 111 holds the cable 52 in contact with its roller 107 and is so positioned over the pivot pin 109 that the contact of the cable and the roller is in vertical alignment with the pin.

As indicated by dotted lines on Fig. 1 the brackets 108 with the rollers 107 are movable upon the pivot pins 109 to guide articles from the main line to the branch line 101. The brackets are moved in unison being connected at the ends furthest from the pins 109 by straps which vary in length as shown particularly in Fig. 1. The five brackets at the right end of the group are joined by a single strap 113 so that they move a uniform distance. The other brackets move distances which gradually decrease, the sixth bracket from the right moving a shorter distance than the five brackets which are joined together and the bracket at the left end of the group moving the shortest distance. This follows by reason of the difference in length of the straps 114, 115, 116, 117, 118 and 119 which respectively join the adjacent brackets. The manner of pivotally securing the straps to the brackets is illustrated in Fig. 5 which shows a pin 120 by which one end of the strap 114 is secured to a bracket 108.

Movement is imparted to the brackets 108 by a thruster 125 of the well known type having push rods 126 connected by a cross bar 127 which is raised and lowered by the mechanism within the thruster which is not shown being no part of the present invention. A cross shaft 128 mounted upon a pair of uprights 102 is oscillated

by the thruster through an arm 129 pivotally attached to the cross bar 127. This movement of the shaft 128 is transmitted to the brackets 108 through an arm 130 fixed at one end of the shaft, 5 a link 131 and a strap 132 fixed to one of the brackets 108. A spring 133 fixed at one end to a cross bar 103 and at the other end to a bracket 108 assists the thruster to return the rollers 107 to the normal position shown in full lines in 10 Fig. 1 so that articles will pass undeflected along the main line.

The thruster 125 here shown is electrically operated by an electric circuit, such, for example, as that shown diagrammatically in Fig. 6. 15 Mounted upon one side rail of the main line and in the branch line 101 are circuit breakers 135, 136 and 137 respectively. The breaker 135 on the main line serves as a safety device and when tripped by contact with an article opens the circuit. The breakers 136 and 137 are arranged 20 in parallel and both must be tripped simultaneously to open the circuit. The breaker 135 is so located that it will be tripped by each article on the main line passing over the deflector junction so that the circuit may not be inadvertently closed and the brackets 108 swung on their pivots when an article is entirely supported by the deflector rollers 107. A switch 138 operable manually or in any well known manner controls the 25 state of the circuit (either open or closed) in the usual way.

Figs. 7 to 15 illustrate means for energizing the thruster 125 which may be employed whenever it is desired that alternate groups 30 continue their travel past the deflector mechanism along the main line, and that the other groups be deflected to the branch line. The groups each consist of a predetermined number of articles, which may differ between the main line groups and the branch line groups. For example as will be pointed out below, the illustrated separating means may make main line groups consisting of five articles each and branch line groups consisting of three articles each.

The separator 152 operates automatically and 45 comprises the following instrumentalities. Mounted upon a structure which comprises uprights 153 at opposite sides of the live rollers and an overhead frame 154 above the rollers and 50 formed by angle bars, is a shaft 155 which is freely rotatable in journal bearings 156. Fixed to the shaft 155 is a ratchet wheel 157 with which a pawl 158 carried by a guard 159 meshes. Suspended from and freely movable about the shaft 155 are a pair of arms 160 one at either side of 55 the ratchet wheel 157. The arms are of such length that a bar 161 carried by the lower ends thereof will be tripped by the articles passing thereunder (see Figs. 7 and 8). Fixed between the arms 160 is a cross block 162 which carries a 60 latch 163 yieldably raised by a spring 164 so that it is held in contact with the teeth at the periphery of the ratchet wheel. When the bar 161 is tripped by an article the arms 160 are swung in 65 the direction of travel of the article and the latch 163 being in contact with a tooth of the ratchet wheel advances the latter one step. After the article has passed the arms resume their normal vertical position, the spring 164 permitting 70 the latch 163 to move back over the next ratchet tooth, the pawl 158 resisting any tendency of the wheel to turn back. In order to limit this backward movement of the arms there is provided a stop plate 165 which is adjustably fixed to a 75 bracket 166 depending from the frame 164.

Mounted on the frame 154 is a control box 170 within which is mounted a rotor 171 fixed at one end of the shaft 155 and a pair of wiper arms 172 mounted upon blocks of dielectric material 173. The rotor is also primarily of dielectric material having, at diametrically opposite sides of the periphery, contact plates 174. The tips of the wiper arms 172 are yieldably held by springs 175 in contact with the periphery of the rotor. The rotor is advanced step by step in unison with 10 the ratchet wheel. In the illustrated construction the wheel includes sixteen teeth so that the passage of sixteen articles will cause one complete rotation of the wheel and of the rotor. The contact plates 174 are of such length that the wiper 15 arms 172 will remain in contact therewith while the ratchet wheel is moved three steps. Thus after three articles have passed the arms contact with the dielectric portions of the periphery of the 20 rotor until five more have passed.

The wiper arms 172 are connected with the thruster 125 as shown in Fig. 15. Thus the thruster will be energized while groups of three 25 articles pass the separator and deenergized while groups of five articles pass so that groups of three are deflected and groups of five are not. The number of articles in the groups obviously depends upon various details as for example the number of teeth in the ratchet wheel and the number and length of the contact plates 174 of the 30 rotor, which may be changed to suit the desired requirements of any installation.

While certain features of this invention have been shown and described in detail it will be understood that the invention is not limited thereto 35 and that various changes may be made in any or all thereof without departing from the spirit and scope of this invention.

I claim:

1. In a live roller conveyer mechanism comprising a plurality of rollers for transporting articles along a line and an endless driving cable one run of which is in contact with and rotates the rollers, means for deflecting articles from the line comprising means for shifting the angularity of 45 certain rollers to change the direction of travel of the articles, said means comprising brackets in which a plurality of successive rollers are supported individually, a pivot for each bracket adjacent one end thereof, a support on which the 50 other end rests and over which it is slidably movable and means for shifting said brackets with their rollers upon such pivots and causing them to slide over the supports thereof.

2. In a live roller conveyer mechanism comprising a plurality of rollers for transporting articles along a line and an endless driving cable one run of which is in contact with and rotates the rollers, means for deflecting articles from the line comprising means for shifting the angularity of 60 certain rollers to change the direction of travel of the articles, said means comprising brackets in which a plurality of successive rollers are supported individually, a pivot for each bracket adjacent one end thereof, a support on which the other end rests and over which it is slidably movable, means connecting each two adjacent brackets and means acting upon one of said brackets for swinging it upon its pivot, causing it to slide over the 65 support therefor, said connecting means simultaneously and similarly moving the other brackets upon their pivots.

3. In a live roller conveyer mechanism comprising a plurality of rollers for transporting arti- 70 75

cles along a line and an endless driving cable one run of which is in contact with and rotates the rollers, means for deflecting articles from the line comprising means for shifting the angularity of 5 certain rollers to change the direction of travel of the articles, said means comprising brackets in which a plurality of successive rollers are supported individually, a pivot for each bracket adjacent one end thereof, a support on which the other 10 end rests and over which it is slidably movable, means for shifting said brackets with their rollers upon their pivots and causing them to slide over the supports therefor, and means tripped by articles on the line for setting said bracket shifting 15 means in operation.

4. In a live roller conveyer mechanism comprising a plurality of rollers for transporting articles along a line and an endless driving cable one run of which is in contact with and rotates the 20 rollers, means for deflecting articles from the line comprising means for shifting the angularity of certain rollers to change the direction of travel of the articles, said means comprising brackets in which a plurality of successive rollers are supported individually, a pivot for each bracket adjacent one end thereof, a support on which the other 25 end rests and over which it is slidably movable and means for shifting said brackets with their rollers upon their pivots and causing them to slide over the supports therefor, said means including a thruster, connections between said 30 thruster and said brackets and a trip actuated by articles on the line for setting said thruster in operation.

5. In a live roller conveyer mechanism comprising a plurality of rollers for transporting articles along a line and an endless driving cable one run of which is in contact with and rotates the rollers, means for deflecting articles from the line comprising means for shifting the angularity of certain rollers to change the direction of travel of the articles, said means comprising pivotally 40 mounted brackets in which a plurality of successive rollers are supported individually, said cable 45 contacting with each of said bracket-supported rollers above the pivotal mountings of the brackets and means for shifting said brackets with their rollers upon their pivotal mountings.

6. In a live roller conveyer mechanism comprising

ing a plurality of rollers for transporting articles along a line and an endless driving cable one run of which is in contact with and rotates the rollers, each of certain of said rollers being mounted in a bracket pivotally mounted adjacent one end 5 thereof, strips secured to each of said brackets adjacent the other ends thereof and connecting each bracket to the bracket next adjacent thereto, and means for positively shifting the angularity 10 of one of said brackets and the roller carried thereby, said strips simultaneously shifting the angularity of the other brackets and the rollers carried thereby.

7. In a live roller conveyer mechanism comprising a plurality of rollers for transporting articles along a line and an endless driving cable one run of which is in contact with and rotates the rollers, each of certain of said rollers being mounted in a bracket pivotally mounted adjacent one end 15 thereof, strips secured to each of said brackets adjacent the other ends thereof and connecting each bracket to the bracket next adjacent thereto, said strips being of different 20 lengths, and means for positively shifting the angularity of one of said brackets and the roller 25 carried thereby, said strips simultaneously shifting the angularity of the other brackets and the rollers carried thereby through varying distances depending upon the lengths of the strips.

8. In a conveyer a live roller section comprising a plurality of rollers for transporting articles along a line and an endless driving cable one run of which is in contact with and rotates these rollers, a branch section leading therefrom and comprising a plurality of parallel rollers extending 30 at an angle to the rollers of the first-named section, said rollers of the first-named section being normally parallel and extending transversely of the line of travel of the articles and being individually movable about stationary pivots and 40 means for swinging said rollers about said pivots through various distances from the normal positions, thus changing the angularity and parallel relation thereof whereby certain of said rollers assume the angularity of the rollers of the sec- 45 ond-named section and the remainder assume angularities intermediate that angularity and the normal position of the rollers.

WILLIAM J. TAYLOR.
